UNITED STATES PATENT OFFICE.

KARL MAIER, OF STUTTGART, GERMANY, ASSIGNOR TO UNION SPECIAL MASCHINEN-FABRIK, G. M. B. H., OF STUTTGART, GERMANY.

THROAT PLATE FOR SEWING MACHINES.

Original application filed June 13, 1925, Serial No. 36,887, and in Germany June 19, 1924. Divided and this application filed October 26, 1926. Serial No. 144,312.

The invention relates to new and useful improvements in throat plates for sewing machines, and more particularly to a throat plate for an over edge sewing machine.

5 An object of the invention is to provide a throat plate having a removable and adjustable section carrying a stitch finger, which provides a very durable support for the finger, and which permits of the finger being 10 adjusted in a direction parallel with the line of feed.

A further object of the invention is to provide said adjustable section of the throat plate with a second stitch finger, which is 15 not only adjustable therewith, but which is also adjustable independently of the adjustments of the main stitch finger.

In the drawings:

Figure 1 is a perspective view showing an 20 over edge stitching mechanism and a work support having my improved throat plate attached thereto, and

Figure 2 is an enlarged perspective view of the throat plate.

25 The invention is directed to a throat plate for an over edge stitching mechanism, that is, a stitching mechanism including a needle and complementary stitch forming devices for an interlocking thread loop about the edge

30 of the fabric. The throat plate is provided with a removable section which is adjustably attached to the main section of the throat plate whereby it may be adjusted in a direction parallel with the line of feed.

35 Mounted on this adjustable section of the throat plate is a stitch finger which lies at one side of the needle and is so disposed that the over edge threads are laid around this stitch finger. The stitch finger terminates a

40 short distance in rear of the needle and is tapered toward its free end so that the thread loops laid over the stitch finger slide off from the stitch finger when the material is moved along by the feeding mechanism.

45 The removable section of the throat plate is provided with a slot extending substantially parallel with the line of feed, and located in this slot is a bar which projects rearwardly from the adjustable section of

50 the throat plate and lies along side of the first named stitch finger. It is, however, spaced from the stitch finger and also spaced from the wall of the main section of the

throat plate. This projecting bar forms a second stitch finger, and the thread loops 55 likewise are laid across the same and slide off from the end thereof when the material is fed.

Referring more in detail to the drawings, the invention is shown as applied to a sewing 60 machine having a plurality of needles 1, a work support 2, a throat plate 3 mounted on the work support, a thread carrying looper 4 beneath the work support, and an over edge thread carrying looper 5. These stitch 65 forming elements produce an over edge stitch. The looper 5 is provided with a plurality of thread eyes arranged one above the other, and each eye carries an independent looper thread, as a result the over edge 70 looper lays a plurality of loops at stitch formation, which loops are nested one within the other.

This stitch forming mechanism and the seam produced thereby form no part of the 75 present invention but are described and claimed in my parent application, Serial Number 36,887, filed June 13, 1925, of which this application is a division, and in my patent No. 1,640,201, granted August 23, 80 1927.

The throat plate 3 is provided with feed slots 6 and 7 in which the feed dog works and the line of feed is of course in a direction lengthwise of these slots. The throat 85 plate 3 is provided with a removable section 8. Said throat plate is recessed so as to form a ledge 9 and the removable section 8 has a portion 10 overlapping the ledge 9. This portion 10 is provided with elongated slots 11, 11. Screws 12 pass through these slots and are threaded in the ledge 9. By loosening the screws 12 the removable section 8 of the throat plate can be adjusted in a direction parallel with the line of feed. 95

The rib 13 of the throat plate which lies between the feed slots 6 and 7 is cut away on its upper face so as to form a supporting ledge 14. The removable section 8 of the throat plate is provided with a projecting 100 part 15 which overlies the ledge 14. This makes a very durable support for the removable section of the throat plate in the region where the needle is operated. The removable section 8 of the throat plate is provided with a stitch finger 16. This stitch 105

finger 16 is tapered at 17 on its lower face, and the said finger projects beyond the rear end of the throat plate so as to provide a slot 18 in which the needle reciprocates. The 5 over edge thread carrying looper lays the thread loops carried thereby over this stitch finger and when the material is moved by the feed dog the thread loops are fed off from the end of the stitch finger. As noted 10 above the over edge looper carries a plurality of threads and thereby a plurality of loops are laid over this stitch finger at each stitch formation. By providing the removable section of the throat plate with a projecting portion 15 a very durable support is formed for this main stitch finger 16. The removable section of the throat plate adjacent the stitch finger 16 is provided with an upwardly and inwardly projecting scroll 19, 20 which serves to infold the edge portion of the material prior to the laying of the thread loops about said edge.

The removable section of the throat plate is provided with a recess or groove 20 in its 25 upper face which extends the full length of the removable section of the throat plate. Located in this groove is a bar 21. The bar 21 projects beyond the rear end of the throat plate so as to provide a second stitch finger 22. The bar is held in the groove by a screw 23 which overlaps the bar and clamps it to the throat plate. This stitch finger is separated from the wall of the main section of the throat plate by a slot 24 and when two 30 needles are used in the stitch mechanism the second needle passes down through this slot 24. By adjusting the section 8 of the throat plate the position of the main stitch finger and also the second stitch finger may be 35 shifted relative to the needles and thus the stitch fingers properly positioned to receive the thread loops and allow the same to slide off from the end thereof. The second stitch finger can be adjusted in the adjustable 40 section of the throat plate and thus the second stitch finger shifted relatively independently of the main stitch finger.

It is obvious that minor changes in the 45 details of construction and the arrangement 50 of parts may be made without departing from the spirit of the invention as set forth in the appended claims.

Having thus fully described my invention, what I claim as new and desire to secure by Letters Patent, is—

1. The combination with an over edge 55 stitch forming mechanism, of a throat plate having feed slots formed therein, said throat plate having a removable section adjustably secured thereto so that said adjustable section can be shifted toward and from the stitch mechanism in a direction parallel with the line of feed from one set position to another, and a main stitch finger carried

by said adjustable section of the throat 65 plate.

2. The combination with an over edge 70 stitch forming mechanism, of a throat plate having feed slots formed therein, said throat plate having a removable section adjustably secured thereto so that said adjustable section can be shifted toward and from the stitch mechanism in a direction parallel with the line of feed, a main stitch finger 75 carried by said adjustable section of the throat plate, said adjustable section of the throat plate having a slot longitudinally thereof, a bar located in said slot and projecting along side of said main stitch finger and forming a second stitch finger, and 80 means for adjustably securing said bar in said slot.

3. A throat plate for sewing machines comprising a main section having feed slots 85 and a recess forming a supporting ledge, a removable section overlying said ledge and provided with elongated slots extending in a direction parallel to the longitudinal axis of the feed slots, screws passing through said 90 slots for adjustably securing the removable section to said supporting ledge, said removable section having a stitch finger projecting therefrom whereby said stitch finger may be shifted in a direction parallel with the line of feed from one set position to another set position.

4. A throat plate for sewing machines comprising a main section having feed slots and a recess forming a supporting ledge, a 100 removable section overlying said ledge and provided with elongated slots, screws passing through said slots for adjustably securing the removable section to said supporting ledge, said removable section having a stitch finger projecting therefrom, and said removable section also having a longitudinal slot in its upper face, and a bar adjustably secured in said slot and projecting along 105 side of the stitch finger to form a second stitch finger.

5. A throat plate for sewing machines comprising a main section having feed slots and a cut away portion on its upper face forming a supporting ledge, said cut away 110 portion extending along side of one of said feed slots and to a point well in rear of the stitch finger, a removable section overlying the supporting ledge on the main section and adjustable lengthwise of the feed slots in a direction parallel with the line of feed, 115 said removable section having a projecting portion tapered to form a stitch finger separated from the main section of the throat plate so as to provide a slot for the needle.

In testimony whereof, I affix my signature.

KARL MAIER.
